UNITED STATES PATENT OFFICE.

CHARLES H. NOWACK, OF CHICAGO, ILLINOIS, ASSIGNOR TO AMERICAN CAN COMPANY, OF NEW YORK, N. Y., A CORPORATION OF NEW JERSEY.

CAN-OPENING DEVICE.

1,359,830.

Specification of Letters Patent. Patented Nov. 23, 1920.

Application filed January 19, 1917. Serial No. 143,205.

To all whom it may concern:

Be it known that I, CHARLES H. NOWACK, a subject of the Emperor of Austria-Hungary, residing in Chicago, in the county of 5 Cook and State of Illinois, have invented a new and useful Improvement in Can-Opening Devices, of which the following is a specification.

This invention relates in general to can 10 opening devices and has more particular reference to devices of this character provided upon the bodies of cans having tight, friction, slip covers, a blacking box being an example of this character of can.

15 An object of the invention is the provision of a readily operable, simply constructed, opening device which will have a single moving part and be of certain and positive operation.

20 Other objects and advantages of the invention will be apparent as it is better understood from the following description when considered in connection with the accompanying drawing illustrating a preferred embodiment thereof.

Referring to the drawings,

Figure 1 is a top plan view of a can provided with an opener embodying my present invention;

30 Fig. 2 is a side elevation of the same, showing the cover in its ordinary closed position;

Fig. 3 is a similar view showing the opening device in the act of raising the cover;

35 Fig. 4 is a section taken substantially on the line 4-4 of Fig. 2;

Fig. 5 is a perspective view of the opening device alone; and

Fig. 6 is a similar view of the blank from 40 which the opening device is formed.

The can shown on the drawing for the purpose of illustrating my invention consists of a body 11 and a tight slip cover 12, the body 11 being beaded at 13 to limit the 45 inward movement of the cover in closing. The upper edge 14 of the body is curled inwardly to stiffen the structure and render more rigid the engagement of the cover with the body when the box or can is first filled 50 with material and placed in commercial use.

The bead 14 is interrupted at 15 at one side of the can and a spherical part 16, having its center in the plane of the bead, is provided. The opening device is secured upon 55 this spherical portion and comprises a cen-

tral spherical part 17 having outwardly extending wings 18, which, as will presently be described, constitute finger grips and provide for the lifting of the cover.

Fig. 6 shows a blank for the formation of 60 the opener. This blank is curved centrally at 17 to its spherical formation and the two wings 18 each consist of a central part 19 of substantially rectangular shape and edge or side parts 21 extending outwardly from 65 the side edges of the part 19. The blank is bent to set off the part 19. The two wings are laid over on the bent lines 22 upon the central part 17, so that their outer edges 23 are brought toward each other. 70 The length of the wings is such that these edges come into substantial contact when so folded, meeting above a central aperture 24 provided for the reception of a pivot 25 to rotatably secure the opening device in place 75 The edges 23 are cut away at 26 and the rivet 27 forming the pivot passes through the opening thus provided, the head 27 of the rivet engaging over the adjacent edges of the wings to hold them in place. There- 80 after the side parts 21 of the wings are bent upwardly into close proximity, as indicated in the drawing, to form outwardly extending finger grips. The side parts of the wings are extended back at 28 in the blank 85 to cause the over-all length of the finger pieces to be greater than the diameter of the body of the opening device, thus providing greater leverage and consequently more easy operation of the opening device in use. 90

The whole device may consist of a single part of sheet metal bent as indicated. The folds 31 in Fig. 1 provide shoulders for engaging the lower edge of the cover to raise the same, when the opening device is turned, 95 and the two finger-piece parts 18 are each secured at two points, viz: at the folds 31 and at the pivot 27, giving a particularly rigid construction well adapted to withstand the strain of forced operation. As the body of 100 the opening device is located between the cover and body of the container, the folds 31 must engage the edge of the cover and the operation is therefore certain and positive. 105

It is thought that the invention and many of its attendant advantages will be understood from the foregoing without further description, and it will be apparent that various changes may be made in the form and 110

construction of the device without departing from the spirit and scope of the invention or sacrificing any of its material advantages, the form hereinbefore disclosed being merely a preferred embodiment thereof.

I claim:

1. A can having a slip cover and a rotatable opener secured thereto beneath said cover, said opener being adapted to engage the edge of the cover upon rotation and having wings extending upwardly and inwardly over its body to provide a finger grip and secured at their edges to the center of said body.
- 10 2. A can having a slip cover and a rotatable opener secured to the body below the edge of said cover, said opener having end wings laid back upon the body of said opener with their edges adjacent, the side edges of said wings being bent upwardly side by side to form a finger grip.
- 15 3. A can having a slip cover and a rotatable opener secured to the body below the edge of the cover extending between the body and cover of said can, said opener having end wings laid back upon the body of said opener with their edges adjacent, the side edges of said wings being bent upwardly side by side to form a finger grip.

4. A can having a slip cover and a rotatable opener pivoted on the can and disposed beneath and behind said cover, said opener having wings bent over its body from opposite edges of the same toward its center and formed into finger grips, said wings being disposed without said cover and adapted to engage its edge at a point of connection with the body upon rotation.

5. A can having a slip cover and a rotatable opener secured thereto, said opener having finger grips formed of wings bent over the body and secured together at the edges thus brought adjacent, the side edges of said wings being bent outwardly to form finger grips.

6. A can having a slip cover and a rotatable opener secured thereto and having wings adapted for the formation of finger grips, said wings being bent over the body and secured by the pivot holding the opener rotatably to the can.

Signed in the presence of two subscribing witnesses.

CHARLES H. NOWACK.
